JOINT PRODUCTION OF PLURALITY OF
GOOD OIL FRACTIONS FROM MINERAL
OILMalcolm H. Tuttle, New Rochelle, N. Y., assignor
to Max B. Miller & Co., Inc., New York, N. Y.,
a corporation of Delaware

Application October 23, 1934, Serial No. 749,519

4 Claims. (Cl. 196—13)

This invention relates to the solvent extraction of mineral oils and more particularly to improved process and apparatus for separating such oils into a naphthenic type or tar fraction and into one or more paraffinic type or lubricating oil fractions, the solvents being recovered therefrom for reuse in the process.

For a statement of the general principles of solvent extraction of mineral oils reference may be had to my Patent 1,912,349 issued May 30, 1933. For a detailed description of a form of apparatus which is well adapted for carrying out the patented process reference may be had to my copending application Ser. No. 698,746 filed November 20, 1933. Such an apparatus will be in part redescribed herein, but it will be understood that the details thereof form no part of the present invention, at least in its broader aspects.

However, whether the apparatus is constructed in accordance with these details or not, it includes generally stated, two principal portions: first, extraction apparatus and second, solvent recovery apparatus. Now, when a batch of high grade lubricating oil is to be produced, given quantities of solvents are preferably employed, and the solvent recovery apparatus is advantageously designed and built for economic recovery of such amounts of solvents. On the other hand, when a batch of lower grade lubricating oil is to be produced, very different amounts of one or both solvents are used, so that the recovery apparatus functions uneconomically if it has been designed and built for handling different quantities of solvents. Large refineries today entail tremendous capital investments, and additional equipment for different grades of product is to be avoided.

A feature of the present invention hence resides in the provision of an improved process of and apparatus for producing different grades of lubricating oil without incurring the disadvantages mentioned.

More specifically, a feature of the invention involves process and/or apparatus for jointly producing from a single charging stock one or more grades of good oil in an economic manner.

Other features, objects and advantages will become apparent in connection with the following detailed description of an example in accordance with the invention, reference being had to the accompanying drawing.

Referring to the drawing, there is shown diagrammatically a form of apparatus constructed in accordance with the principles of the invention, and which involves a number of advantages

from the standpoints of both structural simplicity and efficient operation. This form of apparatus may include an extractor tank 40 subdivided by partitions 41 into a plurality of similar, generally horizontal extracting and settling chambers or pots 43—51, inclusive. Provision is preferably made for introducing solvents into the end chambers 46 and 51 and for introducing an oil to be treated into a chamber 43 intermediate the end chambers. For instance, a solvent for paraffinic oil, such as liquefied propane or other satisfactory solvent, which may be introduced through pipe 52 into chamber 46, while a solvent for the naphthenic oil, such as cresylic acid or other satisfactory solvent, which is immiscible with the paraffinic solvent at operating temperatures, say 60—90° F., may be introduced into chamber 51 through pipe 53. The major portions of the solvents may be recovered from previous operations.

The oil or stock to be treated may be pumped from a tank 54 through pipe 55 into a mixer 56, into which a portion of the lower layer from near the bottom of chamber 47 is fed by a pump (not shown) and line 65, and into which a portion of the upper layer from chamber 44 is fed by pipe line 66, the operations being preferably continuous. These layers contain amounts of paraffinic and naphthenic solvents, as well as dissolved constituents. The mixture is then introduced into the chamber 43 near one end thereof and is allowed to flow toward the other end of the chamber, while stratifying or settling into layers, the construction being such that with a given rate of flow, the settling into layers has ample opportunity to take place to the desired extent, or, in other words, so that the turbulent condition of the mixture at the point of inlet is sufficiently reduced to permit withdrawal of separate layers at points spaced from the inlet.

The lower layer may be withdrawn from the chamber 43 by a pump (not shown) and may be introduced to the chamber 44 through a line 65, in mixture with the upper layer from chamber 45, the mixing being accomplished by another mixing device 56 connected with the chamber 44. The upper layer from chamber 43 may be withdrawn from a suitable point above the bottom of the chamber by line 66, added to a lower layer from chamber 48 and passed into chamber 47 through a mixing device 56 connected with this chamber.

The chambers 44—46 constitute a series of similar chambers which may be termed preceding chambers, and in which the lower or naphthenic

layer from the initial separation of the oil is successively treated by paraffinic solvent introduced into chamber 46 and advanced in countercurrent flow to meet the lower layer from chamber 43. That is to say, the lower layer from chamber 43 is relatively rich in naphthenic constituents, and this layer is treated with solvent for paraffinic oil, the apparatus being constructed so that the paraffinic solvent is richest or freshest 10 in the final stage of the treatment of naphthenic oil, while initially the oil is contacted with solvent which has already taken up considerable paraffinic or lubricating oil constituents.

On the other hand, chambers 47-51 constitute a series of succeeding chambers, similar in construction and operation, wherein the upper or paraffinic layer from chamber 43 is successively treated with naphthenic solvent introduced into chamber 46 and advanced in countercurrent flow 20 to said paraffinic layer which advances from chamber 47 to 51 in succession. It will be understood that the number of chambers may be varied, or that a layer may be passed into a chamber further along than the one next to the chamber 25 from which the layer is withdrawn.

The upper or paraffinic layer from end chamber 51 is withdrawn through back pressure valve 60 and pipe 61 and the lower layer from chamber 46 is withdrawn from near the bottom of this chamber 30 through valve 62 and pipe 63.

The present apparatus is adapted for handling a normally gaseous solvent, such as propane, and maintaining it in a liquid state. Adequate pressure may be maintained, for instance, by pumping 35 the oil and solvents into the system under pressure and limiting the withdrawal of the paraffinic and naphthenic layers to such a rate as to maintain the desired pressure. The extraction apparatus is preferably maintained full of liquid by 40 suitable valves, pumps and other contrivances. Preferably, an equilibrium is established between the solvents and dissolved constituents in each chamber, aided by recirculation where desired.

It is generally desirable to free the raffinate and 45 extract layers of solvents by evaporating or distilling the same from these layers. For this purpose, the raffinate layer may be sent to any suitable evaporator 70 for evaporating propane or other paraffinic solvent. The balance of the 50 raffinate, containing some naphthenic solvent, may be sent to a suitable evaporator 71, where the naphthenic solvent is distilled and recovered for return to the system through line 53. Similarly, the extract layer may be passed through paraffinic solvent evaporator 72 and naphthenic solvent evaporator 73, the solvents being recovered 55 and returned to the system as indicated in the drawing.

It will be appreciated that the solvent recovery system is complementary to the extraction system, and that the former is preferably designed for handling particular quantities of solvents, preferably the maximum amounts required for the production of the high grade paraffinic oil which it is desired to produce in the apparatus. 60

In accordance with the present invention, another grade of lubricating oil may be produced from the same charging stock, without reconstruction of the major portion of the apparatus, 70 by removing from a suitable point in the extraction apparatus a portion of a paraffinic layer. For instance, such a portion may advantageously be removed between the point where the charge oil is introduced and the point where the most 75 paraffinic raffinate is removed. By way of

example, a portion of the upper layer may be removed from chamber 48 through valve 30, line 31 and constant flow controller 32. By means of the constant flow controller, a predetermined ratio can be established and maintained between the quantity of second grade oil produced and the quantity of the paraffinic raffinate removed from chamber 51. It will be understood that the second grade oil fraction thus removed may be stored in a suitable tank and batched through the 10 solvent recovery apparatus 70, 71 between batches of most paraffinic raffinate. In this manner not only may a variety of grades of oil be produced in the same apparatus, but the solvent recovery portion of the apparatus is enabled to operate at full 15 efficiency. In addition, the most paraffinic raffinate is extracted with fresh naphthenic solvent just before it leaves the extraction system, while the second grade oil is extracted with naphthenic solvent which already contains dissolved constituents. Economical use of solvent is thus 20 achieved.

If a third grade oil, or one poorer in quality than the second grade oil, though superior to the charging stock, is to be produced, it may be 25 withdrawn, for instance from extraction chamber 44 through valve 20 and line 21, the rate of withdrawal being controlled by a constant flow controller 22. It will be understood that whatever oil is not withdrawn as second or third grade oil, 30 will continue to flow through the system and be improved in quality until withdrawn as paraffinic raffinate. It is therefore possible, by virtue of the present development, to change over from the production of a single grade of oil to the production of two, or even more grades of oil from a 35 given charging stock.

Merely by way of example, if the charge oil is a Mid-continent residual, topped stock of average characteristics, there may be produced in accordance with the present process a high grade paraffinic type oil having a Saybolt viscosity of 140 at 100° F., a viscosity index of 100, and a carbon residue of less than 0.6, and a second grade oil having a viscosity index of 80-85 and a carbon 45 residue of less than 2.0, when about 300 pounds of liquefied propane per 100 pounds of charging stock, and 200 pounds of cresylic acid per 100 pounds of stock are introduced to the extraction system as indicated, and when the quantity of 50 raffinate withdrawn through line 61 is about equal to the amount of the fraction withdrawn through line 31, although this ratio may vary according to the quantity of each product desired. It will be understood that several different types of oils 55 may be simultaneously produced, if desired.

By operation as above described, a plurality of grades of oil may be produced simultaneously with evaporation equipment operating at full load. Furthermore, a higher viscosity oil can be 60 produced at a higher tar concentration because of the use of naphthenic solvent for finishing the higher grade raffinate before it is used for extraction of mixed stocks. All the extract is washed with paraffinic solvent at a high ratio 65 of paraffinic solvent to naphthenic solvent, but the removal of part of the upper layer before the final extraction of the paraffinic raffinate permits a high ratio of naphthenic solvent to paraffinic solvent and a high ratio of naphthenic solvent 70 to paraffinic oil at this end of the system. Moreover, a continuous operation of the solvent extraction apparatus is made possible.

The terms and expressions which have been employed are used as terms of description and 75

not of limitation, and there is no intention, in the use of such terms and expressions, of excluding any equivalents of the features shown and described, or portions thereof, but it is recognized that various modifications are possible within the scope of the invention claimed.

I claim:

1. A process for extracting a mineral oil by means of counterflowing separable, paraffinic and naphthenic solvents, which comprises continuously counterflowing said solvents by introducing them at spaced points, continuously introducing mineral oil to be treated to said counterflowing solvents at an intermediate point, continuously withdrawing extract and raffinate fractions from points respectively adjacent said first-named points, evaporating said solvents from said raffinate and extract fractions in suitable evaporators, withdrawing an intermediate raffinate fraction at a point between the point where the first-named raffinate is withdrawn and the point of introducing charge oil, and evaporating the solvents from said intermediate raffinate by batches in the same evaporating system employed for freeing the first-named paraffinic raffinate from solvents.
2. A process for extracting a mineral oil by means of counterflowing separable paraffinic and naphthenic solvents which comprises continuously counterflowing said solvents by introducing them at spaced points, continuously introducing mineral oil to be treated to said counterflowing solvents at a point spaced from the point of introduction of naphthenic solvent, continuously withdrawing a paraffinic raffinate fraction from a point adjacent the point of introduction of said naphthenic solvent, continuously withdrawing a naphthenic extract fraction from a point on the opposite side of the point of introduction of the oil to be treated from the point of withdrawing said raffinate, evaporating said solvents from

said raffinate fraction in suitable evaporators, withdrawing an intermediate raffinate fraction at a point between the point where the first-named raffinate is withdrawn and the point of introducing mineral oil to be treated, and evaporating the solvents from said intermediate raffinate in the same evaporating system employed for freeing the first-named paraffinic raffinate from solvents, said intermediate and first-named raffinates being separately batched through said evaporating system.

3. Process as claimed in claim 1, wherein intermediate fraction is withdrawn from a point between the point of introduction of charge oil to be treated and the point of introduction of the paraffinic solvent, and wherein said fraction so withdrawn is treated for removal of both paraffinic and naphthenic solvents.

4. The process of extracting a mineral oil by means of counterflowing paraffinic and naphthenic solvents, in which process said solvents are introduced at spaced points, while the mineral oil to be treated is introduced at a point intermediate said points, and in which process a most paraffinic fraction is withdrawn adjacent the point of introducing the naphthenic solvent, and a most naphthenic fraction is withdrawn at a point adjacent the point of introducing paraffinic solvent, the steps comprising withdrawing, from between the point of introduction of the mineral oil to be treated and the point of withdrawal of the most paraffinic fraction, an intermediate oil fraction which is more paraffinic than said mineral oil, and less paraffinic than the oil withdrawn adjacent the point of introduction of naphthenic solvent, and separating both paraffinic and naphthenic solvents from said intermediate withdrawn oil fraction to produce a final product.

MALCOLM H. TUTTLE. 40
